UNITED STATES PATENT OFFICE

THOMAS A. WRAY, OF UNIVERSITY CITY, MISSOURI

METAL-LATH SUPPORT

Application filed February 13, 1930. Serial No. 428,000.

One of the reasons for the limited use of insulating and sound deadening materials such, for example, as that formed of sheets of flax fiber, in building construction is the difficulty of securing metal lathing to such sheets to receive the finishing coat of plaster, stucco or the like.

The object of my invention is to provide lath supporting means in the form of spacing strips hinged to the insulating sheet so as to fold against it for convenience in shipping and storing, which spacing strips are secured in operative position at right angles to the surface of the sheet by the act of fastening the sheet to the wall or other base to which the insulating material is applied.

In the accompanying drawings, which illustrate lath supporting means made in accordance with my invention, Figure 1 is a horizontal section; Figure 2 is a front elevation; Figure 3 is an enlarged vertical section showing one of the spacing strips in folded position; Figure 4 is a view similar to Figure 3 but showing the strip in extended position; Figure 5 is a bottom plan view of the parts shown in Figure 4; and Figure 6 is a view similar to Figure 5 but showing a modification.

Indicated at 1 is the outer wall of a building carrying studding 2, to which is applied the insulating sheets 3. These sheets are made in width equal to the distance from center to center of two studs and have pivoted to them at intervals, preferably about equal to the width of the sheet, the spacing strips 4. These strips are formed of sheet metal and have their inner edges turned over to form cylindrical beads 5 which provide bearings for the staples 6 pivoting the strips to the sheet, openings 7 being formed in the strips adjacent to the bead for the insertion of the staples. Not only do the beads form bearings for the staples but they strengthen the strips and also prevent forcing of the strips into the relatively soft sheet either when the staples are inserted and clinched, or during the nailing operation hereinafter described.

In order to provide means for securing the spacing strips at right angles to the insulat-

ing sheet in proper position to support the lath, I provide the strips adjacent to each end with a cylindrical bead 8 extending across the strips at right angles to the bead 5 and of the proper internal diameter to receive one of the nails 9 which, when driven through the bead and strip into one of the studs, not only holds the strip in operative position but secures the sheet to the wall by this single nailing operation. By turning the sheet in such direction that the strips swing downwardly when moved from folded to extended position, as shown in the lower part of Figure 2 and in Figure 3, the beads 8 perform a further function as their ends will abut against the sheet, as shown in Figure 4, and automatically hold the strips in horizontal position during the operation of nailing which is thus facilitated. Formed adjacent to the outer edge of the strip are a series of perforations 11 for the passage of wire loops 12, also passing through the openings in the lath 13 and having their ends twisted together to secure the lath against the edges of the spacing strips. The lath may be in the form of expanded metal, wire mesh, or any other form of metallic lathing.

While it is only necessary to provide beads 8 at the ends of the strips, for convenience in manufacture I prefer to place these beads at regular intervals along the length of the strip so that it may be formed continuously and afterward cut into the proper length with a cross bead adjacent to each end. In practice this result may be secured by placing the beads four inches apart as the standard spacing of studs, 12 inches, 16 inches, etc. is in multiples of four inches.

When the cross beads 8 are used to receive the nails, it is necessary to interrupt the edge bead 5 at the points where the cross beads are formed. In Figure 6 I have shown a modification in which the function of the cross bead is performed by a loop 10 punched out from the central part of the strip to receive the nail. When this form is used the edge bead 5 may be made continuous throughout the length of the strip.

It will be seen that by the use of my construction, in which spacing strips are hinged

to the insulating material not only is lath supporting means secured without extra labor in securing the insulation in position, but an additional air space is provided between the insulation and the plaster applied to the lathing, which space adds greatly to the insulating qualities of the completed structure.

While I have described my invention as applied to the outside wall of a building it may with equal facility be used in connection 10 with partition walls, ceilings, etc.

Having fully described my invention, what I claim as new and desire to secure by Letters Patent of the United States is:

1. A bulk sheet of building material provided with a plurality of spacing strips adapted to fold against it; said strips having means to receive a fastener whereby they may be held in extended position.

2. The combination with a lining sheet, of a plurality of spacing strips hinged thereto to fold thereagainst or extend substantially at right angles thereto, and fastening means for securing said sheet in position, said fastening means also holding said spacing strips in extended position.

3. The combination with a lining sheet, of a plurality of spacing strips hinged thereto to fold thereagainst or extend substantially at right angles thereto, and ways in said strips adapted to receive fastening means for securing said lining sheet in position and holding said spacing strips in extended position.

4. The combination with a lining sheet, of a plurality of spacing strips hinged thereto to fold thereagainst or extend substantially at right angles thereto; said strips being provided with beads bearing against the sheet and with ways positioned substantially at right angles to said beads, said ways being adapted to secure fastening means for securing the lining sheet in position and holding said spacing strips in extended position.

5. In a building structure, the combination with a base, of a lining sheet, spacing strips hinged to said lining sheet to fold against the same, fastening means for holding said strips in extended position, and lathing spaced from said lining sheet by said strips.

6. In a building structure, the combination with a base, of a lining sheet, spacing strips hinged to said lining sheet to fold against the same, fastening means for holding said strips in extended position, said means extending through the sheet into said base and securing the sheet thereto, and lathing spaced from said lining sheet by said strips.

7. In a building structure, the combination with a base, of a lining sheet, spacing strips each formed of sheet metal and provided with a bead bearing against said sheet, hinged connections between said beads and the sheet, fastening means for holding said strips in extended position, and lathing spaced from 85 said lining sheets by said strips.

8. In a building structure, the combination with a base, of a lining sheet, spacing strips each formed of sheet metal and provided with a bead bearing against said sheet, staples engaging said beads to attach said strips in hinged relation with said lining, fastening means holding said strips in extended position, and lathing spaced from said lining sheets by said strips.

9. In a building structure, the combination with a base, of a lining sheet, spacing strips each formed of sheet metal and provided with a bead bearing against said sheet, staples engaging said beads to attach said strips in hinged relation with said lining, ways in said strips at right angles to said beads, fastening means extending through the sheet into the base to secure the lining in position, and lathing spaced from said lining sheet by said strips.

In testimony whereof, I hereunto affix my signature, this 11th day of February, 1930.

T. A. WRAY.
